UNITED STATES PATENT OFFICE

EDWARD KIRSCH, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CANDY-PULLING MACHINE.

Application filed August 24, 1925. Serial No. 51,971.

This invention relates in general to improvements in the art of conditioning viscous pliable substances, and relates more specifically to improvements in the construction and operation of machines for pulling and otherwise working candy stock or the like.

An object of the invention is to provide improved mechanism for conditioning viscous pliable material such as candy stock. Another object of the invention is to provide a candy pulling machine which is simple and compact in construction, and which is highly efficient in operation. A further object of the invention is to provide candy stock conditioning mechanism of the floating pin type, which is durable in structure and in which the operating mechanism is formed to resist excessive wear. Still another object of the invention is to provide improved pin structure for candy stock working machines of the floating pin type. These and other objects and advantages of the present improvement will be apparent from the following description.

A clear conception of an embodiment of the invention and of the operation of mechanism constructed in accordance therewith, may be had by referring to the drawing accompanying and forming a part of this specification in which like reference characters designate the same or similar parts in the various views.

Fig. 1 is a front view of an improved candy pulling machine.

Fig. 2 is a side elevation of the improved candy pulling machine.

Fig. 3 is a fragmentary vertical section through one of the pin driving disks of the improved candy pulling machine.

Fig. 4 is a fragmentary vertical section through the center of the improved candy pulling machine.

Fig. 5 is an enlarged part sectional view of one of the candy pulling pins of the improved machine.

As specifically illustrated in the drawing, the improved candy pulling machine comprises generally an upper casing 2 having a pair of laterally spaced substantially parallel bearings 26 formed integral therewith and located entirely therewithin; a pair of parallel horizontal main shafts 24 rotatably supported in the bearings 26 within the casing

2; a peripherally notched disk 3 formed integral with the forward end of each of the shafts 24 and having peripheral engagement with circular openings in the front of the casing 2; three floating pins 5 associated with the peripheral notches 4 of the disks 3 and movable thereby about the disk axes; a base 21 forming a support for the casing 2 and for a working table 22 disposed in front of the machine beneath the projecting ends of the pins 5; a prime mover illustrated as an electric motor 17 adjustably associated directly with the base 21; and a train of gearing connecting the motor 17 with the disk supporting shafts 24.

The upper casing 2 besides supporting the bearings 26 of the shafts 24 and providing peripheral bearings for the disks 3, has adjoining rear openings of sufficient size to permit removal therethrough of spur gears 10 which are secured to the shafts 24 directly adjacent to the bearings 26. The spur gears 10 mesh with each other and are disposed closely adjacent to a cover 23 which encloses the rear portion of the casing 2 and provides end bearings for the shafts 24, this cover also providing bearings for other transmission gearing.

The candy pulling pins 5 which are of the hook type, have rear ends which are rotatably supported in rollers 9 as shown in Fig. 5. The rollers 9 have medial portions of enlarged diameter and have adjacent end portions of smaller diameter, the roller portions of smallest diameter being engageable directly with the notches 4 of the disks 3. The enlarged medial portions of the rollers 9 are adapted to engage the surfaces of a pin transferring tumbler 6 as shown in Fig. 1, the tumbler 6 being formed to automatically transfer the successive advancing pins 5 from the notches 4 of one disk 3 to the cooperating notches of the other. The tumbler 6 is supported upon a pivot 34 and is oscillatable about this pivot, the degree of movement of the tumbler 6 being limited by a stop pin 7 which engages lower abutments formed on the tumbler. A helical spring 33 engages a front surface of the tumbler 6 and surrounds the pivot 34 thereof, this spring serving to frictionally retain the tumbler 6 in any position of adjustment until the same is positively shifted by an advancing

roller 9. The rollers 9 are retained upon the ends of the pins 5 by means of a removable cap 30 as shown in Figs. 3 and 5.

The pins 5 project away from the disks 3 and are overhung with respect to these disks, extending horizontally over the table 22. Embracing each pin 5 adjacent to its supported end, is a circular guard plate 8 having a frusto-conical outer surface. 10 These guard plates 8 extend laterally away from the pins 5 and over the adjacent faces of the disks 3 and of the upper casing 2. The disks 8 may be frictionally retained upon the pins 5 and are freely removable 15 therefrom.

One of the spur gears 10 which are secured to the shafts 24 and which intermesh with each other, meshes directly with a pinion 11 secured to a counter shaft to which 20 a transmission gear 12 is also secured. By virtue of this arrangement, the gears 10 and hence the disks 3 are rotatable at the same speed and in opposite directions thus causing the notches 4 of one disk 3 to cooperate with the corresponding notches 4 of the other disk, at all times. The transmission gear 12 meshes with a driving pinion 13 which is secured to a counter shaft the rear end of which projects beyond the 25 cover 23 and is drivingly connected to a grooved sheave 14. The sheave 14 is drivingly connected to a lower sheave 16 by means of a plurality of independent V-belts or bands 15 which may be formed of reinforced rubber. The driving sheave 16 is secured directly to the shaft of the driving motor 17 which is supported within the base 21 upon an adjustable base plate 18. The base plate 18 is guided upon the side 30 walls of the base 21 and has openings therein which are penetrated by vertical threaded rods 19 secured at their upper ends to lugs formed integral with the base 21. Nuts 20 coact with the lower threaded 35 portions of the rods 19 and permit utilization of the weight of the motor base 18 and of the motor 17 to vary the tension on the driving bands.

During normal operation of the candy pulling machine, the motor 17 is operating 50 to transmit continuous rotary motion to the disks 3 in opposite directions, through the sheave 16, bands 15, sheave 14, pinion 13, gear 12, pinion 11, and gears 10. As the 55 disks 3 rotate, the pins 5 associated with the peripheral notches 4 thereof, are caused to revolve about the axes of rotation of the disks 3. When the pins 5 approach the tumbler 6, they are automatically transferred from the notch 4 of one disk 3 to the cooperating notch 4 of the other disk as illustrated in Fig. 1. The transferred pin 5 is then urged along the axis of the receiving or right hand disk 3 as shown in 60 Fig. 1, and eventually strikes the laterally 65

projecting lower arm of the tumbler 6 which is located directly in the path of movement of the pin, and automatically throws the tumbler 6 to its extreme opposite position where it is retained by the spring 23. The tumbler 6 is then in a position to transfer the upper approaching pin 5 from the right hand disk to the other disk 3. The pin 5 so transferred again actuates the tumbler 6 by striking the laterally projecting opposite lower arm thereof. In this manner the successive pins 5 are transferred from one disk 3 to the other and are carried about the disk axes in a figure 8 course. The candy stock is placed upon the projecting ends 70 of the moving pins 5 above the table 22, and is pulled and worked in such a manner that air is effectively embedded in the stock and produces a desired change in the condition thereof. After the candy stock has 75 been sufficiently conditioned, the machine may be stopped and the stock removed from the pins 5 thus placing the mechanism in condition for the reception of a fresh batch 80 of stock. 90

During such operation of the machine the guard plates 8 effectively prevent the stock from entering the notches 4 and the bearing surfaces between the disks 3 and the casing 2. The rollers 9 permit effective 95 propulsion of the pins 5 with minimum wear. By rotatably supporting the pins 5 within the rollers 9, these pins are permitted to adjust themselves to accommodate the pull thereon. The pins 5 may be 100 removed from the rollers 9 by removal of the caps 30, and the entire machine may be readily disassembled by removal of the cover 23 and of the spur gears 10. 105

It should be understood that it is not desired to limit the invention to the exact details of construction and operation herein shown and described, for various modifications within the scope of the claims may occur to persons skilled in the art. 110

It is claimed and desired to secure by Letters Patent:

1. In combination, a pair of rotary disks, a roller positively movable by direct engagement with said disks and periodically transferable from one disk to the other, and a pin rotatably associated with said roller only. 115

2. In combination, a roller, rotary means directly engaging said roller to positively urge the same along a figure 8 path, and a pin rotatably associated with said roller only. 120

3. In combination, a roller, means comprising a pair of rotary disks and a tumbler for directly engaging and for positively urging said roller along a figure 8 path, and a pin rotatably supported by said roller only. 125

4. In combination, a pair of disks having peripheral notches, means for rotating said 130

- disks in opposite directions, a roller movable by direct engagement with the notches of said disks and periodically transferable from one disk to the other, and a pin rotatably supported by said roller only. 5. In combination, a pair of rotary disks having peripheral notches, a roller movable by direct engagement with the notches of said disks, a tumbler for periodically transferring said roller from a notch of one disk to a cooperating notch of the other, and a pin rotatably supported by said roller only. 6. In combination, a roller, means for alternately revolving said roller about spaced parallel axes in opposite directions, a tumbler for periodically transferring said roller from one path of revolution to the other, and a pin rotatably supported only by and concentrically of said roller. 7. In combination, a roller, means for urging said roller along a definite path, and a candy pulling pin supported only by and freely rotatable relatively to said roller. 8. In combination, a roller having end portions of reduced diameter and having a medial enlarged portion, means forming a pair of adjoining curved tracks with which said reduced roller portions are cooperable, means cooperable with said enlarged medial roller portion for transferring said roller from one of said tracks to the other, and a pin rotatably supported in said roller. 9. In combination, a roller having end portions of reduced diameter and having a medial enlarged portion, means forming a pair of adjoining curved tracks with which said reduced roller portions are cooperable, an oscillatory tumbler cooperable with said enlarged medial roller portion for transferring said roller from one of said tracks to the other, and a pin rotatably supported in said roller only. 10. In combination, a pair of rotary disks having peripheral notches, means forming a track surrounding each of said disks, a roller having reduced end portions and an enlarged medial portion, said roller being movable by engagement with the notches of said disks and the reduced portions thereof being rollable along said tracks, a tumbler cooperable with said medial enlarged roller portion for periodically transferring said roller from a notch of one disk to a cooperating notch of the other, and a pin rotatably supported within said roller only.

In testimony whereof, the signature of the inventor is affixed hereto.

EDWARD KIRSCH.
